UNITED STATES PATENT OFFICE

ABRAHAM KRAMER, OF NEW YORK, N. Y.

LIGHT FIXTURE HAVING REMOVABLE PANELS

Application filed April 4, 1929. Serial No. 352,473.

My present invention relates to light fixtures, and, more particularly, to an improvement in a light fixture provided with readily removable and replaceable reflector panels.

Although light fixtures, such as chandeliers, have been constructed in the past in such a manner that the glass reflector sections thereof could be removed from the chandelier frame independently of one another, yet, no one has ever before devised or designed a light fixture, be it chandelier, wall bracket or lamp shade, which was provided with reflector panels that could be replaced selectively, with but a single, movement of the individual panel. The fact is, in the past, and prior to my present invention, considerable manipulation was necessary to remove a panel from the fixture frame. Further, the constructions were crude, expensive and readily destroyed due to excessive manipulation and bending, or twisting, of the parts retaining the reflector panels in position.

Now, I have discovered and designed a light fixture which is truly simple in construction, embodies a plurality of reflector panels in any position, and yet is so devised that merely a single motion of the hand serves to remove one of the panels from the fixture. In short, not only have I invented a light fixture that readily lends itself to a multitude of ornamental designs, but one that may be assembled or dis-assembled in a plurality of single motions.

Accordingly, it is one of the main objects of my present invention to provide a light fixture of simple construction, so designed and constructed that a minimum expenditure of effort and materials is required to assemble all the component reflector panels into the fixture frame.

Another important object is to provide a light fixture, so constructed as to lend itself to the assembly of a design of highly ornamental appearance, and comprising a frame composed of a plurality of members cooperating to receive reflector panels, and each of the members being provided with a groove whereby an individual reflecting panel may be disposed into its predetermined position

by merely sliding the panel along the grooves of its associated pair of frame members.

Other objects of the invention are to provide a light fixture, whether it be a chandelier, wall bracket or lamp shade, which is simple in construction, economical to manufacture, composed of members coordinated to produce a pleasing and highly ornamental design, and particularly distinguished by the fact that its component reflector panels may be readily removed or replaced by a motion of the hand involving a minimum expenditure of effort or knowledge of assembling a light fixture.

The novel features which I believe to be characteristic of my invention are set forth in particularity in the appended claims, the invention itself, however, as to both its organization and method of assembly will be best understood by reference to the following description taken in connection with the drawing in which I have indicated diagrammatically organizations whereby my invention may be carried into effect.

In the drawing:

Fig. 1 is a front view of a wall bracket embodying my invention.

Fig. 2 is a sectional view taken on line 2—2 of Fig. 1, looking in the direction of the arrows.

Fig. 3 is a detail in perspective of a grooved frame member.

Fig. 4 is a perspective view of a modified form of grooved member.

Fig. 5 is a sectional view of the modification in Fig. 4.

Referring to the accompanying drawing in which like characters of reference indicate the same parts in the different views, Fig. 1 shows a plurality of frame members, built up into a particular design, it being understood that any desired design may be formed of the frame members. A back member 1, in this case, provides the support about which the frame members are arranged. I have shown in Fig. 1, a wall bracket, it being understood that the back 1 is affixed to a wall. Of course, the frame members can be arranged as a chandelier or a lamp shade, it being a matter of mechanical skill to change from one form to the other.

The back 1 has affixed to each of its two opposite, longitudinal edges, a frame member 2. Each member 2 is provided with a groove 3 of a length equal to the length of the member. Each grooved member is open ended at one end, as at 4, and closed at the opposite end, as at 5. Thus, the two sides 6, 6 of each member 2, cooperate with the end 5 to provide a receiving and retaining means 10 for the edge of reflector panel 7.

As shown in Figs. 1 and 2 the members 2, 2 are inclined towards each other, in order to be in alignment with similar grooved members 2', 2'. The frame members 2', 2' are 15 exactly similar in height and construction to the members 2, 2. Adjacent the members 2', 2' are disposed two additional frame members 2'', 2'', in this case, providing the front panel. These members 2'', 2'' are of 20 the same height and construction as the frame members 2 and 2'.

A reflector panel 7, of translucent glass, and of a shape, for example, as shown in Fig. 1, is disposed in position between the 25 members 2'', 2''. The panel 7 is inserted into position by sliding it into the grooves of the members 2'', 2'', until the bottom of the side edges of the panel rest on the closed ends 5, 5 of the grooved members; as shown 30 by dotted line, the side edges of the panel 7 are thus positioned in the grooves of members 2'', 2''.

In the same way, a panel 7 can be inserted between each pair of members 2, 2' on either 35 side of the fixture. By means of proper spacing wires 8, (omitted in Fig. 1 for the sake of simplicity of showing, and shown in Fig. 2), any design of frame members may be built up. For example, in Fig. 1 a plurality 40 of grooved frame members, of shorter length than the members 2, 2', 2'', are shown inwardly spaced therefrom by the wires 8, and arranged in three groups. One of the groups consists of six members disposed above the 45 members 2, 2', 2'', comprising two members 9, 9, affixed to the backing 1, and inclined in a direction parallel to the inclination of members 2, 2. In alignment with the members 9, 9 are two members 9', 9', spaced 50 from the former members by the wires 8.

Two front frame members, parallel to members 2'', are affixed to the members 9', 9'. These front members 9'', 9'', are shown retaining a reflecting panel 7' which is similar 55 to panel 7 in every respect, except in size. As in the case of members 2, 2', 2'', members 9, 9', 9'' cooperate to receive three panels, which rest on the closed ends 5 of the latter members.

Below the members 2, 2', 2'', are two telescoped groups of frame members. Affixed to the backing 1, are two grooved members 60 10, 10, having top open ends 4 and closed ends 5, as described in connection with members 9 and 2. In alignment with members

10 are two members 10', 10', and they are spaced therefrom by wires 8 (not shown). Front members 10'', 10'' are affixed to the members 10', 10', and are shown retaining a reflecting panel 7'', which rests on the closed 70 ends 5 of the frame members 10'', 10''.

In the same manner, six additional grooved frame members 11, 11', 11'' are positioned below the members 10, 10', 10'', the two rear members 11, 11 being spaced from the members 10, 10 by wires 8 (not shown).

A reflecting panel 12 is shown retained in position between members 11'', the panel resting on the closed ends 5 of the said members.

From the preceding description, it is apparent that there are provided several groups of frame members, the frame members 2-2', 2''-2'', 2'-2 constituting one group; frame members 9-9', 9''-9'', 9'-9 constituting a second group; members 10-10', 10''-10''; and 10' 10 constituting a third group; and frame members 11-11', 11''-11'', and 11'-11 constituting a fourth group. Each group of frame members is thus disposed concentrically about a vertical axis common to all the groups, and which axis is disposed substantially in the plane of the back 1.

Furthermore, each frame member is parallel to each and every other member of the same or other groups, so that each group is disposed parallel to each other group. In this way, there is provided a plurality of parallel groups of frame members which are grouped about a common axis lying, in the modification shown herein, in the plane of the back 1. Also, it is to be noted that each panel has both its extremities extending beyond the extremities of its supporting grooved frame members. This enables each panel to be withdrawn from between its supporting frame members with but a single motion, and without obstruction by any other panel.

Now, it will be obvious that it is the simplest matter to assemble the panels in a fixture of my invention, it being only necessary to slide a particular reflecting panel between its appropriate grooved frame members, until it rests on the closed end 5 of the frame members. To remove it is just as easy. Merely pulling a panel upwardly removes it. Thus, each panel 7', 7, 7'' and 12 in Fig. 1, may be removed independently of one another, it being especially observed that even in the most complicated chandelier design, an inner panel, as 12, in Fig. 1, may be easily removed by simply grasping the top of the panel from the top of the fixture and pulling it upwardly. Should a panel break, it is merely required that a new panel be ordered from the manufacturer, and when received be instantly and easily replaced. This arrangement thus avoids the necessity of sending the entire fixture back to the manufac- 130

turer, where the panels are soldered, or otherwise affixed, to one another. Obviously in the case of large ceiling chandeliers, an arrangement of my invention secures greatly beneficial results in ease of panel removal, 5 cleaning, replaceability and appearance of a group of crystals.

In Figs. 4 and 5, I have shown a modified form of grooved member, in which the closed end 5' is made adjustable, thus permitting longitudinal adjustment of a reflecting panel, and, additionally, the insertion of a panel from the bottom of a pair of grooved members by removing the adjustable ends 5' or 15 lowering them sufficiently to permit the insertion of the panel edges in the grooves 4' of the pair of members.

As shown in Figs. 4 and 5, each frame member is affixed to a post 15, tapped at its bottom by a screw 16 having an enlarged head 17, with a portion 5' providing the supporting end for the panel. It is to be understood that where two grooved members are adjacent each other, the screw 16 could have a 25 head 17, providing with a second enlarged, circular portion 5', which latter portion would form the supporting end of the second grooved member. The head 17 can be made ornamental, so as to have it conform 30 with the rest of the fixture design.

While I have indicated and described only two modifications for carrying my invention into effect, it will be apparent to one skilled in the art that my invention is by no means 35 limited to the particular organizations shown and described, but that many modifications in the arrangements may be employed, without departing from the scope of my invention as set forth in the appended claims.

40 What I claim is:—

1. A light fixture comprising a plurality of parallel groups of spaced frame members, said frame member groups being disposed about a common axis, and said frame members being provided with panel retaining 45 grooves.

2. A light fixture comprising a plurality of parallel groups of spaced frame members, said frame member groups being disposed about a common axis, and said frame members being provided with panel retaining grooves, a panel supported between each pair of frame members solely in the grooves thereof, at least one extremity of each panel 55 extending beyond the extremities of its supporting frame members.

3. A light fixture comprising a plurality of parallel groups of spaced frame members having grooves therein, said frame member groups being disposed about a common axis, and panels in each group of frame members disposed between adjoining pairs thereof, said panels being retained in place solely in the grooves of said frame members.

60 4. A light fixture comprising a plurality

of parallel groups of spaced frame members having grooves therein, said frame member groups being disposed about a common axis, and panels in each group of frame members disposed between adjoining pairs thereof, 70 said panels being retained in place solely in the grooves of said frame members, the extremities of each panel projecting beyond the extremities of its retaining frame members.

5. A light fixture comprising a plurality of parallel groups of spaced frame members, said frame member groups being disposed about a common axis, and said frame members each being parallel to any other frame 75 member of any group, the said frame members being provided with panel retaining grooves.

6. A light fixture comprising a plurality of groups of spaced, parallel frame members, 80 said groups being concentric about a common axis and each of said groups having its frame members relatively offset in the direction of said axis, a panel disposed between each pair of adjoining frame members, each frame member being provided with a panel retaining 90 groove.

Signed at New York city in the county of New York and State of New York this 1st day of April, A. D. 1929.
